UNITED STATES PATENT OFFICE.

JAMES J. MACDAID, JR., OF BRIGHTON, MASSACHUSETTS, ASSIGNOR TO DENNISON MANUFACTURING COMPANY, OF FRAMINGHAM, MASSACHUSETTS, A CORPORATION OF MASSACHUSETTS.

CREPE-STRIP DECORATION.

Application filed March 22, 1926. Serial No. 96,482.

This invention relates to a crepe strip decoration, and more particularly to a decoration of this kind where a crepe strip is provided with cut out portions forming 5 recurrent series of figures.

Strips of figures of this general type have been made by folding up a strip of paper and then cutting out either the edge or center parts of the folded paper, then 10 unfolding the strip. This results in a series of similar figures of any desired pattern. The great difficulty with decorations of this type has been that they curl up, either longitudinally of the strip or the individual 15 projecting portions of the figures transversely thereof.

Among the objects of the present invention are to provide a strip having a supporting band and integral interconnecting portions between adjacent figures, whereby 20 when the strip is extended, longitudinal curling is prevented; also to crepe the strip of paper transversely thereof, whereby the individual figures are strengthened and curling 25 transversely of the strip is prevented.

A further object is to provide a strip of paper of one color having cut out portions and a strip of another color cemented or otherwise suitably secured to one side of the 30 perforated strip, so that portions of the second strip will be visible through the cut out portions of the first strip. This second strip will serve also as a reinforcement for the first strip. By making the 35 strips of creped paper it is possible to use a much thinner paper than would be possible if ordinary paper were used.

The word "color" as used in the present specification and claims is not meant to be 40 limited to red or blue etc., or any combination of them but may also include black, white and gray etc.

Other objects of the present invention will appear from the detailed description 45 which follows and will be pointed out in the appended claims:

In the drawings:

Fig. 1 is a view of a crepe strip decoration embodying the invention; and 50 Fig. 2 is a similar view of another embodiment of the invention including two back strips of different colors.

Referring to the embodiment of the invention shown in Fig. 1, 1 represents the sup-

porting band with diamond shaped figures 55 2 depending therefrom and connected thereto by integral portions 3 formed by cutting out portions 4. These figures are also connected to each other at the sides at 5. The figures are creped transversely of the strip 60 as shown at 6. Thus it is seen that when the strip is extended in use as shown the figures will be prevented from individually curling longitudinally of the strip by the integral supporting band 1 and the connected portions 65 5. The creping 6 will substantially prevent curling transversely of the strip in the well understood manner.

Fig. 2 shows a modification of the invention formed in the shape of cats' heads and 70 adapted particularly for Hallowe'en decorations, although it is obvious that any other desired form of figure might be resorted to. The supporting band 1 is used as in the other form shown and the figures 7 are 75 attached thereto at two points 8 for each figure, and attached to the adjacent figure at a plurality of points 9. This provides for a more substantial lateral support of the figures than where only one lateral connection is employed as shown in Fig. 1. The figures are each provided with eye openings 10 and a mouth opening 11 and behind these openings are cemented or otherwise suitably secured strips 12 and 13 respectively. 80 These strips are colored differently from the main strip so that a distinct color effect is had through the eye and mouth openings. In the present embodiment the main strip is black, the strip 12 is green and the strip 13 red. The strips 12 and 13 in the present 85 instance are made of crepe paper, but this is not necessary as any other suitable paper or other material might equally well be employed. Strips 12 and 13 serve also as a reinforcement for the main strip. The creping 90 is the same as in the previously described modification.

It is obvious that many modifications of the basic idea can be made both as to the 100 design of the figures and the color of the paper used. Also in making up double strips similar to that shown in Fig. 2, only one backing strip need be used, and on the other hand, any desired number may be 105 used, two being shown only by way of example. I do not wish to be limited, therefore, except by the following claims.

I claim:—

1. An article of manufacture comprising an elongate strip of paper having openings cut to form a series of figures extending longitudinally of the strip, the figures being joined together at intervals spaced transversely of the sheet to restrain the figures from individually curling longitudinally of the strip, and each figure being creped along lines extending transversely of the strip to restrain the figures from curling transversely of the sheet.

2. An article of manufacture comprising an elongate strip of paper having openings cut to form a series of figures extending longitudinally of the strip, the figures being joined together at intervals with integral interconnecting portions spaced transversely of the sheet and spaced from one lateral margin of the sheet so that each figure projects beyond the last interconnecting portions adjacent said margin, and each figure being creped along lines extending transversely of the strip to restrain said projecting portions of the figures from curling transversely of the sheet.

3. An article of manufacture comprising a strip of paper having recurrent portions cut out to form a series of openings, with intermediate integral interconnecting portions spaced at intervals along one dimension of the strip and creped along said dimension to minimize curling.

4. An article of manufacture comprising a strip of paper having cut out portions, the resulting strip comprising a supporting band along one margin of said strip and a series of recurrent portions connected at intervals to said supporting band and adapted to depend therefrom and be connected to each other at one or more points transversely of said strip, each of said recurrent portions being creped along lines extending transversely of said strip to minimize curling.

5. An article of manufacture comprising a strip of paper having cut out portions, the resulting strip comprising a supporting band along one margin of said strip and a

series of recurrent portions, each portion being connected to said supporting band and also having an integral connection with the next adjacent portion lengthwise of said strip, the portions being creped transversely of said strip to prevent curling.

6. An article of manufacture comprising a strip of paper having cut out portions, the resulting strip comprising a supporting band along one margin of said strip and a series of recurrent portions, each portion being connected to said supporting band and also having an integral connection with the next adjacent portion to restrain said portions from individually curling longitudinally of the strip, and each portion being creped transversely of the strip to reinforce it and to prevent curling transversely of the strip.

7. An article of manufacture comprising an elongate strip of paper having portions cut out to form a recurrent series of figures, extending longitudinally of the strip, the figures being joined together at intervals transversely of the strip, each figure being creped transversely of said strip to prevent curling, and one or more additional strips of paper of a different color than said first-mentioned strip and secured to one side thereof so that they may be seen from the other side through the cut out portions of the first-mentioned strip.

8. An article of manufacture comprising a strip of paper having recurrent portions cut out to form a series of figures, with intermediate integral interconnecting portions spaced at intervals along one dimension of the strip and creped along said dimension to minimize curling, and an additional strip of paper of a different color from said first-mentioned strip secured to one side thereof whereby it is visible through the cut out portions of said first-mentioned strip and whereby the additional strip serves also to reinforce the first-mentioned strip.

Signed by me at Boston, Massachusetts, this 19th day of March, 1926.

JAMES J. MACDAID, JR.
